SEWING MECHANISM

William H. Lewin, New York, N. Y.

Application December 9, 1936, Serial No. 114,914

6 Claims. (Cl. 112—205)

My invention relates to a new and improved sewing mechanism.

One of the objects of my invention is to provide a new and improved sewing machine for making zig-zag stitches in which the needle and looper operate in a fixed path and in invariable timing.

Another object of my invention is to provide an improved machine for this purpose, said machine having improved means for feeding the work in a generally forward direction, and for reciprocating the work laterally relative to the normal line of forward feed, resulting in the production of zig-zag stitches.

Another object of my invention is to provide a simple attachment which can be manufactured at low cost and which can be easily applied to any sewing machine which produces straight stitches, so as to convert said machine into a zig-zag machine. In particular, and without limiting the invention, the attachment can be readily applied to the well-known sewing machine designated in the trade as "Singer 95-40" in order to convert said machine to a zig-zag sewing machine.

Another object of my invention is to provide a sewing machine for making either zig-zag or straight-away stitches, at will, which will have the same reliability and the same high speed of operation in making zig-zag stitches as the ordinary machine which makes a straight stitch only.

Another object of my invention is to provide an improved feed dog, and a novel combination of feed dog and needle plate, and to provide novel means for operating the same in unison.

While I show the invention as applied to a lock-stitch machine, I do not wish to be limited to any particular type of sewing machine.

Zig-zag sewing machines have been on the market for many years, in which the needle-bar, in addition to being vertically reciprocated, was vibrated laterally from side to side, across the line of feed, as in the "Singer 107 W" type. This necessitated mounting the sewing-hook or looper in such manner that the plane in which it turned coincided with the plane of lateral vibration of the needle-bar, that is, said plane was perpendicular to the line of forward feed. In such an arrangement, a distinct loss of efficiency and speed was unavoidable, and said lateral motion resulted in noise, vibration, and the rapid wear of the needle-bar and its related mechanism, and this lateral motion also made it impossible to secure a constant or uniform adjustment between the sewing-hook and the needle. These disadvantages and other disadvantages which are familiar to

those skilled in the construction and repair of these machines, ultimately reduced the speed of operation to about 2200 stitches per minute.

However, the ordinary sewing machine in which the needle-bar is not reciprocated laterally, and in which the sewing-hook rotates in a plane exactly parallel to the line of feed, is capable of producing reliable stitching at speeds of 4000 stitches per minute.

According to the invention herein disclosed, I have secured an efficient and reliable zig-zag stitch at speeds up to 4000 per minute, using the essential parts of a standard sewing machine, and without laterally reciprocating the needle-bar or changing the essential sewing mechanism, which makes this high-speed of operation possible without undue noise, vibration, or rapid wear.

My invention is shown in connection with the accompanying drawings and description.

Fig. 1 is a side elevation of the improved machine.

Fig. 2 is a bottom plan view of Fig. 1.

Fig. 3 is a detail elevation, partly in section showing the needle plate and feed dog at the left-hand extreme of their lateral travel.

Fig. 4 is a view similar to Fig. 3, showing the needle plate and feed dog at the right-hand extreme of their lateral travel.

Fig. 5 is an end elevation, taken at the right-hand side of Fig. 1.

Fig. 6 is a perspective view of a casting which can be connected to the underside of the bed-plate of a standard machine, said casting having some of the operating parts of the device mounted therein.

Fig. 7 is a sectional view, on the line 7—7 of Fig. 1, showing certain details of the feed mechanism.

Fig. 8 is a detail sectional view, on the line 8—8 of Fig. 7, showing certain details of the feed mechanism.

Fig. 9 is an end elevation, partially in section, on the line 9—9 of Fig. 1, showing certain of the connecting means for reciprocating the needle plate laterally.

Fig. 10 is a top plan view on the line 10—10 of Fig. 1, showing certain details of the needle plate, feed dog, and cover plate.

Fig. 11 is a detail perspective view showing a part of the needle plate and the feed dog.

Fig. 12 is a detail sectional view on line 12—12 of Fig. 2.

Fig. 13 is a perspective view of the needle plate and its slide-rod extension.

Fig. 14 is a perspective view of part of the feed

mechanism in which the double-headed arrows "X", and "Y", and "Z" denote the various movements of the feed dog.

Fig. 15 is a detail sectional view of part of the needle plate, showing one of the depending studs and rollers which laterally reciprocate the feed dog.

The invention is illustrated as embodied in a sewing machine of standard type and having many standard parts. Since this machine is well-known on the market as "Singer 95-40", it is unnecessary to state the details of those parts thereof which remain unchanged in the invention.

15 Referring to Fig. 1, said machine has a hollow arm 1, bolted to a bedplate 2, said arm 1 carrying a main shaft 3, which is provided with a balance wheel 4. Main shaft 3 carries a bevel gear 5, meshing in a one-to-one ratio with a bevel gear 5a of the vertical jack shaft 6, which is provided near its lower end with a bevel gear 7, meshing in a two-to-one ratio with the bevel gear 1a of the sewing-hook shaft 8. Shaft 6 is supported near its lower end by an auxiliary bearing 9, which forms part of the casting 10, (illustrated separately in Fig. 6). That part of shaft 6 which protrudes through bearing 9, carries another bevel gear 11, which meshes in a one-to-two ratio with a bevel gear 12, carried on a short horizontal jack shaft 13, suitably journaled in the bearings 14a and 14b, (Fig. 2), which forms part of casting 10. Said casting 10 is bolted to the underside of the bedplate 2 by means of four bolts 15, which also serve to attach arm 1 to the upper side of bedplate 2. Shaft 35 13 also carries a cam 16, of suitable profile, which cooperates with the forked end 17a of a connecting-rod 17. Said connecting-rod 17 is pivotally connected to a link 18, as shown in Fig. 2, by means of an adjustable cone-screw 19, and its lock nut 19a.

Said link 18 is pivotally connected to another link 20, by means of an adjustable cone-screw 21, and its lock nut 21a. Said link 20 is rigidly fastened to a shaft 22, which can be turned a few degrees in either direction, in its bearing 23, by means of a crank arm 24, rigidly fastened to said shaft 22, in order to adjust said shaft 22 to vary the throw of the connecting rod 17 from zero to maximum, thereby determining the width 50 of the zig-zag stitches. To enable the operator to make this adjustment conveniently, crank arm 24 is connected to a thumb-screw 25, by means of an extension arm 26, which is pivotally connected to arm 24 by means of a pivot-screw 27, having a lock-nut 27a. The shank of the thumb-screw 25 is threaded into the extension arm 26 through a suitable slot 28, cut in the hollow arm 1 and said thumb-screw 25 can be tightened at any desired setting of shaft 22, so as to hold shaft 60 22 in any of its adjusted positions.

Fig. 1 shows rod 17 in neutral position and it is shown in Figs. 3 and 4, in the position of maximum throw.

Referring to Figs. 1 and 2, connecting-rod 17 terminates at its left-hand end in a yoke 17b, which is pivotally connected by means of a tapered pin 29 to a perforated lug 30 (Fig. 13), which is rigidly fastened by means of two screws 30a, to the underside of slide-rod 31, slidably mounted in a suitable guideway (Figs. 9 and 10) milled into the bedplate 2. Said guideway has edges 32.

Said rod 31 has inclined side-edges, and the edges 32 of the guideway are correspondingly inclined. A clearance hole 33 (Figs. 2 and 10) is

also cut through the bedplate 2, through which the lug 30 protrudes so that said lug can be connected to the yoke 17b by means of said pin 29, whose tapered surface fits snugly in the tapered bore of the lug 30. Said pin 29 is adjustable to 5 allow for wear, by means of its threaded extension 29a and its lock nut 29b (Fig. 12).

The left-hand end of the slide-rod 31 carries the needle plate N, rigidly fastened thereto by two screws 34, (Fig. 13), so that the needle plate N 10 necessarily partakes of the lateral to-and-fro motion imparted to the slide-rod 31 by means of the reciprocating motion of the connecting-rod 17.

Figs. 3 and 4 show the respective positions of 15 the novel parts at the ends of the left-hand and right-hand lateral movements of the needle plate and feed bar.

The needle plate N fits in the guideway 35 of the bedplate 2 (Fig. 10), and the assembly is 20 covered by a thin cover plate 36, fastened to bedplate 2 by means of four screws 37, and having an aperture 38, to expose a section of the needle plate N containing the elongated needle-hole 62, and to expose the rows of teeth F₁ and F₂ of the feed dog F. These teeth protrude through the respective slots N₁ and N₂ of the needle plate N, in order to contact with the under surface of the work, and to feed the work, in the upper position of said feed dog. The presser-foot P holds the work down and said presser foot is of 30 sufficient width to allow for the side-to-side movement of the feed dog F.

Sufficient bearing surface is given the slide-rod 31 in its guideway, so that the needle plate N 35 attached thereto has no appreciable shake, or lost motion, and the latter is therefore given sufficient clearance in the guideway 35, and beneath the cover plate 36, so as to avoid friction at these points.

A detachable section 36a of the cover plate 36 40 is riveted to the movable slide-plate 39 (Fig. 2) slidably mounted in the guideway 35, and yieldingly retained therein by the spring 40.

As shown in Fig. 7, the underside of needle plate N is provided with downwardly projecting 45 studs 41a and 41b, secured to the needle plate by means of screws 42a and 42b. Turnably mounted on these respective studs are rollers 43a and 43b, which register with notches 44a and 44b, respectively, of the feed dog F. Said rollers are 50 of sufficient depth to allow for the up-and-down movement of the feed dog F, said movement being indicated by the double-headed arrow "X" in Fig. 14. Likewise the said notches are of sufficient length to allow for the back-and-forth movement of the feed dog F in the direction of ordinary feed of the material and reverse thereto, as indicated by the double-headed arrow "Y". The direction of ordinary forward feed of the cloth is indicated by arrow "W".

As shown in Fig. 14, the feed dog F is rigidly fastened to the feed-bar 45, which is integral with the sleeve 45a, which is turnably and slidably mounted on the shaft 46, which is fixed to the crank arms 47a and 47b, integral with the rock 65 shaft 48. There is sufficient clearance between the ends of the sleeve 45a and the adjacent crank arms 47a and 47b, to allow for the side-to-side movement of the feed-bar 45, which is indicated by the double-headed arrow "Z". Said side-by-side movement is imparted to said feed-bar by means of the rollers 43a and 43b of needle plate N cooperating respectively with the notches 44a and 44b of the feed dog F.

Conventional means are employed to secure 75

the back-and-forth movement of the feed dog F. The rock shaft 48 is rockably mounted at its ends on adjustable cone bearings 49a and 49b (Fig. 2), and said shaft 48 is rocked by a crank arm 50, 5 pivotally connected to a rod 51, which is suitably reciprocated from the main shaft 3. The amplitude of its rocking movement, which determines the length of the switch, is varied from zero to maximum by conventional means, and is controlled by the operator through the usual thumb-screw 52.

Likewise, the up-and-down movement of the feed dog F is conventionally secured by means of a crank arm 53, which carries a stud 54, on 15 which roller 55 is mounted. Said roller cooperates with the forked end 45b of the feed-bar 45 (Fig. 7). Crank arm 53 is carried by rock shaft 56 (Fig. 2), which is rockably mounted at its ends on adjustable cone bearings 57a and 57b, and said 20 shaft 56 is rocked by means of crank arm 58, pivotally connected to a rod 59 which is suitably reciprocated from the main shaft 3. The roller 55 of the crank arm 53 is of sufficient length to allow for the side-to-side movement of the feed-bar member 45b, said movement being indicated 25 by double-headed arrow "Z" (Fig. 14).

The ordinary needle-bar 60 moves needle 61, through the needle-hole 62, and the needle cooperates with the sewing-hook S in the usual 30 manner. The bobbin case, bobbin case base and positioning finger, all of which are conventional, are not shown.

Referring to Fig. 11, it will be noted that the serrations or teeth of the feed dog F are cut at 35 an angle of about 45 degrees relative to the longitudinal axis A—A and arrow W, so that when feeding the work forwardly and also laterally to the left, for instance (referring to Fig. 11), the working edges of the row of teeth F₁ will be presented to the work approximately at right angle to the resultant movement of the work; and when feeding the work forwardly and also laterally to the right, the working edges of the row of teeth F₂ are likewise presented to the work at right 40 angles to the resultant movement of the work.

The operation of the mechanism is as follows:—

The feed-dog F is raised vertically so that the rows of teeth move upwardly through their respective slots in the needle plate to engage the work against the yielding pressure of the presser foot. The feed dog now moves forwardly (away from the operator), and at the same time the needle plate is shifted laterally to the right, so 50 as to shift the cloth and the feed dog in the same direction. This combination of the simultaneous forward and lateral movements of the feed dog produces a resultant feeding movement of the work along a line which is inclined 55 to the right of the longitudinal axis A—A, and at an angle which depends upon the relationship between the setting of the amplitude of the zig-zag stitch and the setting of the length of the straight-away stitch. At the completion of 60 the forward movement of the feed dog, which coincides with the completion of its lateral movement, the feed dog is moved beneath the level of the top of the needle plate, thereby losing contact with the work. The work is held immovable by the pressure of the presser foot against the needle plate, which remains stationary while the feed dog is now returned in an idle stroke 65 towards the operator in a line parallel to, and to the right of, axis A—A. At the conclusion of 70 the return or idle stroke, the feed dog is again 75

moved upwardly to engage the work as before. It is again moved forwardly, but during this stroke the simultaneous lateral motion of the needle plate and feed dog takes place to the left of line A—A, so that the work is given a resultant feeding movement along a line which is inclined to the left of the axis A—A, and at an angle equal to that of the line of the first resultant feeding movement. At the completion of this simultaneous forward and lateral movement of the feed dog, it is again lowered beneath the level of the top of the needle plate and it is returned idly toward the operator, but this time in a line parallel to and to the left of, axis A—A. The same 10 cycle of movements is repeated. 15

In the type of machine specifically illustrated herein, the needle-bar has only the usual vertical reciprocating movement. However, the attachment may be applied to a machine in which the needle bar moves in any direction. For convenience, the direction in which the work would be fed, if the needle plate and feed dog did not have said lateral reciprocating movement, may be designated as the direction of straight-away forward feed. The sewing hook or looper is turned or rocked or otherwise moved in a fixed plane. This plane is preferably, but not necessarily, parallel to said direction of straight-away forward feed. Said plane may be adjusted relative to said direction, but said plane does not 20 change after adjustment and during the operation of the machine. 25

The cam 16 has dwell portions which operate to hold the needle plate in fixed position, at predetermined intervals, and while the needle is in the work. While the needle plate is thus held against lateral movement, the feed-dog is moved back in its idle stroke. Hence the lateral movement of the needle plate is intermittent. 35

While I have shown a feed-dog, it is to be 40 understood that other types of feeding devices could be substituted, whenever a feed-dog having a four-motion movement relative to the needle-plate, is specified in any part thereof, including 45 the claims.

The movement of the feed dog (excepting its lateral to-and-fro movement) may be designated as the usual four-motion movement of the feed dog. The movement of the feed dog while it is in its upper position may be designated as a feeding 50 stroke, and the movement of the feed dog while it is in its lower position may be designated as an idle stroke. 55

When the feed dog is in its lower position, the tops of its teeth may be below the bottom of the needle plate, or the top portions of said teeth may be located between the top and bottom surfaces of the needle plate.

Whenever I refer to a needle plate in the 60 claims, it is to be understood that I wish to include any equivalent work-support. It will be noted that the needle plate is connected directly to the feed device, by means of the studs 41a and 41b (including the rollers), and the notches 65 44a and 44b. This direct connection makes it unnecessary to provide a plurality of cams or the like, for producing the lateral movement of the needle plate, and the lateral movement of the feed dog. Likewise and as shown in Fig. 11, the 70 teeth of the feed dog have longitudinal axes, said axes being inclined to the longitudinal axis of the feed dog.

Likewise, I do not wish to be limited to a feed dog having two separated rows of teeth, as I may 75

use a feed dog having a single row of teeth, or having more than two rows.

Likewise, the invention can be applied to a machine having one or more needles, and it can 5 be used with embroidery machines.

In the embodiment specifically illustrated, the needle-bar has a reciprocating movement in the direction of its longitudinal axis, and this movement, for convenience, is designated as a vertical 10 reciprocating movement. However, it would not be departing from the invention if the needle-bar had a movement or movements in addition to said reciprocating movement, or if the needle-bar was mounted to reciprocate in a line which 15 was not vertical.

Likewise, the invention is applicable to machines in which a curved needle is oscillated about an axis. For convenience, the movement of the needle may be designated as a to-and- 20 fro movement.

I have shown a preferred embodiment of my invention but it is clear that numerous changes and omissions could be made without departing from its spirit.

25 I claim:

1. A sewing machine having a needle mounted for to-and-fro movement, a needle plate mounted for to-and-fro movement, the direction of movement of the needle plate being at an angle to the 30 direction of movement of the needle, a movable feed device, operating mechanism adapted and operative to actuate the needle to-and-fro and to move the needle plate to-and-fro and to impart a four-motion movement of the feed device relative to the needle plate, direct connecting means 35 between said needle plate and said feed device so that the feed device is moved to-and-fro in unison with the to-and-fro movement of the needle plate, said operating mechanism being operative 40 and timed to move the feed device forwardly in a feeding stroke and simultaneously to move the needle plate and the feed device laterally in one direction, then to move the feed device rearwardly in an idle stroke while the needle plate is held 45 against substantial movement, then to move the feed device forwardly in a feeding stroke while the needle plate and the feed device are moved in a second direction which is opposite to the first-mentioned direction, and then to move the feed device rearwardly in an idle stroke while the needle plate is held against substantial movement.

2. A sewing machine having a needle mounted for to-and-fro movement in a direction which 55 makes an angle with a horizontal plane, a needle plate mounted for to-and-fro movement in a horizontal plane, a movable feed device, said feed device being movable forwardly and rearwardly and vertically up-and-down relative to the needle plate, means directly connecting said needle plate and said feed device for simultaneous to-and-fro movement, when the needle plate is moved to-and-fro.

3. A sewing machine having a needle bar 65 mounted for vertical reciprocating movement, a needle plate mounted for reciprocating lateral movement in a horizontal plane, a feed dog having teeth which are located to project through an open portion of the needle plate, said feed dog being movable forwardly and rearwardly and vertically up-and-down relative to the needle plate, means connecting said needle plate and said feed dog for simultaneous lateral movement, 70 said teeth of said feed dog having longitudinal 75

axes which are inclined relative to the longitudinal axis of the feed dog.

4. A sewing machine having a needle bar actuated by a main shaft for vertical reciprocating movement, a needle plate mounted for lateral reciprocating movement in a horizontal plane, a feed dog having teeth which are located to project through an open part of said plate, said sewing machine having a bed plate, a bearing device connected to the underside of said bed plate, a first vertical shaft connected to said main shaft and having the lower end thereof supported in said bearing device, a second and horizontal shaft supported in said bearing device, intermeshing gears connecting said first 10 shaft and said second shaft, a link driven from said second shaft and connected to the needle plate and reciprocating the needle plate intermittently and laterally, means adapted to regulate the amplitude of lateral movement of said 15 needle plate, said feed dog having longitudinal notches, said needle plate having depending members which are located in said notches so that the feed dog is moved laterally in unison with the needle plate, and supplemental mechanism adapted to impart a four-motion movement 20 to said feed dog relative to said needle plate.

5. In a sewing machine, the sub-combination of a needle plate mounted for lateral reciprocating movement in a horizontal plane, said needle 30 plate having an open part, a feed dog mounted for four-motion movement and having teeth which are located to project through said open part during part of the four-motion movement of said feed dog, mechanism operative to impart 35 said four-motion movement to the feed dog, said needle plate having depending lugs which are located in corresponding recesses of the feed dog, so that the feed dog is also moved in unison with said lateral reciprocating movement of the needle plate.

6. A sewing machine having a bed plate, a bearing device connected to the underside of said bed plate, said sewing machine having a main shaft, a first vertical jack-shaft, gears connecting said main shaft and said first vertical jack-shaft in a first ratio, the bottom end of said first jack-shaft extending below said bed plate and being supported in said bearing device, a second jack-shaft supported in said bearing device below the work plate, gears connecting said first jack-shaft to said second jack-shaft in a second ratio which is lower than the first ratio, a link driven from the second jack-shaft, a needle plate mounted for lateral reciprocating movement in a horizontal plane and connected to and driven intermittently in said movement by said link, a hook mounted on a hook-shaft, the first jack-shaft being connected by gears to the hook shaft in a third ratio which is higher than the first 50 ratio, a needle mounted for vertical reciprocating movement, said hook being mounted for turning in a predetermined plane, said needle plate having an open part, a feed dog mounted for four-motion movement relative to the needle plate and 55 having teeth located so that they project through said open part during part of the four-motion movement of said feed dog, mechanism adapted and operative to impart said four-motion movement to the feed dog, said needle plate having depending lugs which are located in longitudinal recesses of the feed dog so that said feed dog is moved laterally in unison with the lateral reciprocating movement of the needle plate, the 60 operating mechanism for the needle plate and 65

for the feed dog being operative and timed to move the feed dog forwardly in an upper feeding stroke and simultaneously to move the needle plate and feed dog laterally in one direction, then 5 to move the feed dog rearwardly in a lower idle stroke while the needle plate is held against substantial lateral movement, then to move the feed dog forwardly in an upper feeding stroke while the needle plate and feed dog are moved laterally

in a second direction which is opposite to the first-mentioned direction, and then to move the feed dog rearwardly in a lower idle stroke while the needle plate is held against substantial lateral movement, and mechanism for regulating the 5 stroke of said link, said mechanism including an additional jack-shaft which is mounted below the bed plate in said bearing member.

WILLIAM H. LEWIN.
